UNITED STATES PATENT OFFICE.

LOWELL M. KING, OF OREGON, ILLINOIS.

RAILWAY-GATE APPARATUS.

1,240,149.

Specification of Letters Patent. Patented Sept. 11, 1917.

Application filed February 9, 1916. Serial No. 77,322.

To all whom it may concern:

Be it known that I, LOWELL M. KING, a citizen of the United States, residing at Oregon, in the county of Ogle and State of Illinois, have invented new and useful Improvements in Railway-Gate Apparatus, of which the following is a specification.

This invention relates to improvements in railway gate apparatus and has particular application to a train controlled gate apparatus for use at highway crossings and the like.

In carrying out the present invention, it is my purpose to provide railway gate apparatus for use at highway crossings and the like wherein as long as the trackway is free of traffic the barriers controlling the highway will be in elevated or open position and the barriers across the trackway in lowered or closed position so as to prevent horses, cattle, etc., from traversing the trackway and wherein the barriers controlling the highway will be automatically lowered and the barriers across the trackway similarly elevated when a train approaches the crossing, thereby stopping traffic over the highway across the track and enabling the train to proceed over the crossing without endangering life or property.

It is also my purpose to provide apparatus of the class described which will be entirely automatic in operation and train controlled and wherein the component parts will be so arranged and correlated as to reduce the possibility of derangement to a minimum and enable access to be readily had to the mechanism for the purposes of cleaning and repairing.

With the above and other objects in view, the invention consists in the construction, combination and arrangement of parts hereinafter set forth in and falling within the scope of the claim.

In the accompanying drawings; Figure 1 is a top plan view of a crossing showing my invention installed, parts of my gate apparatus being shown in section and other parts in elevation, the section being taken on the line 1—1 of Fig. 3.

Fig. 2 is a sectional view on the line 2—2 of Fig. 1.

Fig. 3 is a similar view on the line 3—3 of Fig. 1.

Fig. 4 is a diagrammatic view showing the motor and circuit connections, the parts being shown in the positions they occupy

when the highway gates are elevated and the track gates lowered.

Fig. 5 is a similar view showing the parts in the positions they occupy when the highway gates are lowered and the track gates elevated.

Referring now to the drawings in detail, 1 designates a railroad trackway, while 2 indicates a highway crossing intersecting the trackway 1. Arranged at each side of the highway upon one side of the trackway are housings A and B, while arranged at each side of the highway at the opposite side of the trackway are housings C and D, 60 the housings A and C being disposed upon the same side of the highway and the housings B and D at the other side, as clearly illustrated in Fig. 1 of the drawings.

Arranged in the casing C and suitably secured therein is an electric motor 3 and fixed upon the armature of the motor 3 is a pinion 4 meshing with a gear 5 fixed upon a shaft 6 journaled in a bearing bracket 7 carried by one side wall of the casing C and 70 disposed adjacent to the upper end of the casing. Fixed to the opposite end of the shaft 6 is a spur gear 8 meshing with a toothed quadrant 9 fixed upon a shaft 10 journaled in a bearing bracket 11. Also 75

fixed upon the shaft 10 adjacent to the quadrant 9 is a bevel pinion 12 meshing with a similar pinion 13 keyed upon a shaft 14 journaled in a bearing bracket 15 and arranged at right angles to the shaft 6. The 80 shafts 6 and 10 are disposed in planes parallel with each other and with the trackway 1, while the shaft 14 is arranged parallel with the highway and at right angles to the trackway. Secured to one side wall of the 85

casing C below the quadrant 9 is an electromagnet 16 or other electroresponsive holding device and fixed to the lower edge of the quadrant 9 is an armature 17, while disposed in the path of movement of the lower 90 edge of the quadrant 9 is a single pole two-way switch embodying a blade 18 pivoted at one end as at 19, and contacts 20 and 21 adapted to be engaged by the blade 18, the blade 18 normally engaging the contact 21 100 and being held in such engagement by a spring 22. Extending longitudinally of the track rails and parallel therewith are contact strips 23 of a length greater than the width of the highway and adapted to be engaged by the flanges of the wheels of a car 105 passing over the crossing. Leading from

105

110

one of the contact rails 23 is a conductor 24 connected to the blade 18 at the pivot point thereof, while from the contact 21 normally engaged by the blade 18 leads a conductor 25 connected to one terminal of the motor 3. The remaining terminal of the motor 3 is connected with one side of a suitable source of electrical energy by means of a conductor 26, while from the remaining side of such source extends a conductor 27 connected to the other contact strip 23. The contact 20 is connected with one terminal of the electro-magnet 16 by means of a conductor 28, while from the remaining terminal of the electro-magnet leads a conductor 29 terminally connected to the conductor 26.

When a train approaches the crossing and is passing the crossing the wheels and axles bridge the contact strips 23, thereby closing the circuit of the motor 3, current flowing from one side of the source of energy, through the conductor 26, the motor, conductor 25, contact 21, switch blade 18, conductor 24, across the bridged contact strips 25 and back to the other side of the source of energy by way of the conductor 27. Upon the energization of the motor the quadrant 9 is swung downwardly, thereby rotating the shafts 10 and 14 and in the downward movement of the quadrant the lower end thereof kicks the blade 18 out of engagement with the blade 21 and into engagement with the contact 20, thereby placing the magnet 16 in circuit with the source of energy and cutting the motor 3 out of service. The current for the magnet 16 flows from one side of the source of energy, through the conductors 26 and 29, the magnet 16, the conductor 28, the contact 20, the blade 18, conductor 24, across the bridged contact rails 23, and back to the other side of the source of energy by way of the conductor 27. When the magnet 16 is energized, the pole thereof acts upon the armature 17 to hold the quadrant 9 in operated position so as to prevent the return of the parts to normal position.

Secured to one side of the quadrant 9 is a plate 30 and pivoted to the lower end of the plate 30 and depending therefrom is a link rod 31 having the lower extremity thereof pivoted to one leg of a bell crank lever 32 fulcrumed upon a bracket 33 mounted within the casing C adjacent to the lower end thereof. Pivoted within the lower end of the casing A is a bell crank lever 34 and connecting the remaining leg of the bell crank lever 32 to the corresponding leg of the bell crank lever 34 is a connecting rod 35 extending across the trackway below the latter. The remaining leg of the bell crank lever 34 is connected through the medium of a link rod 36 with an arm 37 fast upon one end of a shaft 38 journaled in a bearing bracket 39 secured to the side wall of the

casing A adjacent to the upper end thereof. This shaft 38 is arranged parallel with the trackway and disposed at right angles to the shaft 38 is a shaft 40 journaled in a bearing bracket 41 carried by the side wall 70 of the casing adjacent to the upper end thereof. The corresponding ends of the shafts 38 and 40 are provided with meshing bevel pinions 42 whereby motion may be transmitted from the shaft 38 to the shaft 75 40. Connected to the bell crank lever 32 in the casing C at the pivot point of such lever is one end of a horizontal shaft 43 extending longitudinally of the trackway below the surface of the highway and into the casing 80 D, as clearly illustrated in Figs. 1 and 2 of the drawings. Fixed to the end of the shaft 43 within the casing D is an arm 44 connected by means of a link rod 45 with an arm 46 secured to one end of a shaft 47 journaled in a bearing bracket 48 carried by one side wall of the casing D adjacent to the upper end thereof. This shaft 47 is arranged longitudinally of the trackway and is connected through the medium of bevel pinions 49 with a shaft 50 arranged at right angles to the trackway and journaled in the bearing bracket 51 carried by the side wall of the casing D. Depending from the ends of the shaft 43 within the casing is an arm 90 52 connected through the medium of a rod 53 with one leg of a bell crank lever 54 pivoted within the casing B at the lower end thereof and the remaining leg of the bell crank lever 54 is connected through the medium of a rod 55 with an arm 56 fixed upon one end of a shaft 57 journaled in a bearing bracket 58 carried by one side wall of the casing B adjacent to the upper end thereof. The shaft 57 is arranged parallel 100 with the lines of rails of the trackway and is connected through the medium of bevel gears 59 with a shaft 60 journaled in a bearing bracket 61 carried by one side wall of the casing B. This shaft 60 is arranged at 110 right angles to the shaft 57, as clearly illustrated in Fig. 1 of the drawings.

Suitably secured to the shafts 10, 14, 38, 40, 57, 60, 48 and 50 respectively are gates or barriers 62. The barriers 62 carried by the respective shafts that are parallel with the highway are lighter than the barriers carried by the shafts parallel with the trackway so that the weight of the barriers on the last-mentioned shafts will keep such barriers normally in lowered position and hold highway barriers in elevated or open position, as shown in Fig. 1 of the drawings.

When the motor is energized as previously described, motion is transmitted to the various shafts carrying the barriers through the connections hereinbefore described so that the barriers across the trackway will be elevated and the barriers controlling the highway lowered, and when the wheels of the 130

train disengage the contact rails 23 to de-energize the magnet, the barriers controlling the trackway will gravitate to lower or closed position and elevate or open the barriers controlling the highway.

5 In the present instance, the upward movement of the quadrant 9 is cushioned by means of a spring 63 or other shock absorbing device so as to prevent the transmission 10 of shock or jar to the mechanism.

While I have herein shown and described one preferred form of my invention by way of illustration, I wish it to be understood that I do not limit or confine myself to the 15 precise details of construction herein described and delineated, as modification and variation may be made within the scope of the claim and without departing from the spirit of the invention.

20 I claim:

In railway gate apparatus for use at highway crossings and the like, barriers movable across the highway at opposite sides of the track, barriers movable across the 25 trackway at opposite sides of the highway, connections between all of said barriers

whereby the first-mentioned barriers may be moved to inactive position when the last-named barriers are in closed position and the last-named barriers moved to open position 30 in the closing of the first-mentioned barriers, a segment connected to one of said barriers, an electric motor, a pinion on the motor shaft meshing with said segment, an electric circuit for said motor adapted to be 35 closed by a train traversing the trackway in the vicinity of the crossing, an electro-magnet connected across the motor circuit, a switch for breaking the motor circuit and establishing the circuit of said magnet and 40 disposed in the path of movement on said segment, and an armature on said segment adapted to engage said magnet upon the operation of said switch whereby the barriers may be held in operated position 45 succeeding the operation of the motor.

In testimony whereof I affix my signature in presence of two witnesses.

LOWELL M. KING.
